[57] CLAIM

The ornamental design for a pivoted vessel for the solar heating of water, substantially as shown and described.

DESCRIPTION

FIG. 1 is a front perspective view of the pivoted vessel for the solar heating of water of my new design.

FIG. 2 is a side view thereof with portions broken away to reveal interior detail, the opposite side being substantially identical.

FIG. 3 is a top view thereof.

FIG. 4 is a sectional view taken along the line 4—4 of FIG. 2.
